METALLIC RECEPTACLE

Charles E. Bertels, San Francisco, Calif., assignor of one-half to William W. Breite, San Francisco, Calif.

Application February 15, 1936, Serial No. 64,124

5 Claims. (Cl. 220—1)

This invention relates to the class of metallic receptacles and pertains particularly to receptacles of the type in which liquid substances are marketed.

5 At the present time there are being marketed a variety of liquid preparations in cans, which formerly were put on the market in bottles. These liquids, such as beer, for example, are frequently consumed directly from the containers 10 but it is not convenient to consume the liquids in this manner when they are put up in cans, for the reason that it is difficult for the consumer to hold the can to the mouth after an outlet has been made in the end wall thereof.

15 The primary object of the present invention is to provide an improved can structure having an end wall of novel construction which will permit the contents of the can to be drunk directly therefrom after a suitable opening has been formed in the end wall, instead of having to pour out the contents into a glass for consumption.

Another object of the invention is to provide an improved can having novel closure means for 20 a dispensing opening whereby the internal pressure of the can will assist in maintaining the opening closing device in position.

25 The invention will be best understood from a consideration of the following detailed description taken in connection with the accompanying drawing forming part of this specification, with the understanding, however, that the invention is not confined to any strict conformity with the showing of the drawing but may be changed or modified so long as such changes or modifications 30 mark no material departure from the salient features of the invention as expressed in the appended claims.

In the drawing:—

35 Figure 1 is a view in top plan of a metallic receptacle constructed with the improved form of head embodying the present invention.

Figure 2 is a sectional view taken upon the line 2—2 of Figure 1.

40 Figure 3 is a view similar to Figure 2 but showing a modification of the head formation.

Figure 4 is a view similar to Figure 2 but showing a punch out closure for the dispensing opening.

45 Figure 5 illustrates the application of the punch out closure to a head of the type shown in Figure 3.

Referring now more particularly to the drawing, wherein like numerals of reference designate 50 corresponding parts throughout the several views,

the numeral 1 indicates a can or other type of metallic receptacle body of the type normally employed for marketing foods or liquid refreshments, the numeral 2 indicating an end wall secured in the usual manner to the end of the 5 cylindrical wall body.

The present invention contemplates the provision of an end wall for the receptacle body which is inset to an extent to permit the end of the receptacle to be put to the mouth so that, if the 10 wall has been provided with a suitable outlet opening, the contents of the receptacle can be drained therefrom over the end edge directly into the mouth thus making it unnecessary to transfer the receptacle contents to a glass before 15 drinking.

The numeral 3 indicates an end wall having a portion of its area flat, as indicated at 4, while the adjacent portion curves upwardly toward the edge of the receptacle, as indicated at 5. As 20 shown, this flattened portion is placed at such a distance from the adjacent end of the can as to permit the said end edge to be placed between the lips so that the contents of the can can be conveniently consumed and in this form of end wall 25 it is intended that an opener of the cutting type be used for forming an outlet such as is shown in Figure 1 and indicated by the numeral 6. Openers are now provided which may be engaged over the flange or rim 7 of the can and used to cut an 30 opening directly through the adjacent end wall of the can so that the liquid contents can be poured off and after using an opener or perforating instrument of this character it will be apparent that the liquid contents of the can may be 35 conveniently drained into the mouth.

In Figure 3, there is illustrated a modification of the wall structure shown in Figures 1 and 2 wherein the can end wall 8 is formed straight across the can body but at a substantial distance 40 inwardly from the end of the can. In both forms the walls are integral with flange or skirt portions 9 which extend longitudinally of the can to be crimped over the end edge thereof to form a sealing rib or flange 7.

45 Figures 4 and 5 illustrate in association with the two types of walls shown in Figures 2 and 3 but here designated 3a and 8a respectively, discharge openings 10 already formed in the walls and closed by the frictionally held cap 11 which 50 is forced thereinto. This cap 11 is of the type commonly used for closing outlet openings of receptacles, having a flange 12 which prevents it being forced completely through the opening but, in the present instance, it is extended into the 55

opening from the inside of the receptacle so that the flange will engage against the inner side of the end wall instead of the outside. It will be apparent that a frictionally held closure member of the type illustrated would not be satisfactory where the receptacles are used for selling beer or any other liquid which is maintained in the receptacle under pressure but by inserting the closure cap from the inside of the receptacle the internal pressure will operate to keep the cap firmly in place and when it is desired to dispense the can contents it is only necessary to force the cap inwardly with some suitable instrument.

From the foregoing it will be readily apparent that receptacles constructed in accordance with the present invention serve the double function of containing the merchandised liquid in the desired manner until required for use and providing a convenient means for drinking the receptacle contents directly from the receptacle. This form of receptacle is particularly desirable for taking refreshments on hunting, fishing or other trips or for picnic use where it is desirable that as little equipment as possible be carried.

I claim:—

1. A liquid-holding can having an end closed by a wall set inwardly from the end of the can body and having a wide flange extending therefrom to the end edge of the can body, said flange extending along the inner surface of the can body and in contact therewith, the edges of the flange and the can body being sealed together, the said wall and flange forming an outwardly opening cup of substantial depth in the end of the can to receive liquid from the interior of the can when said wall is provided with an opening therein.

2. A can having a body and a top end wall set

inwardly from the end of the can body to provide an outwardly opening and a clearly-defined cup of substantial depth for drinking purposes, said wall having an opening therein formed immediately adjacent to the rim of the cup and placing the interior of the body in communication with the cup, the upper end of the opening being at no point higher than the bottom of the cup.

3. A can having a body and a top end wall set inwardly from the end of the can body to provide an outwardly opening and a clearly-defined cup of substantial depth for drinking purposes, said wall having an opening therein formed immediately adjacent to the rim of the cup and placing the interior of the body in communication with the cup.

4. A beer can having a depressed top to form a drinking cup with a drinking lip and a relatively smooth and unobstructed bottom adjacent the lip and having a bead on the outside of the drinking lip permitting an opener to pry under the lip for indenting an adjacent portion of the bottom toward the wall of the can to form a hole adjacent the drinking lip, the cup being adapted to accommodate the initial overflow caused by the release of inside pressure due to the puncturing of the can.

5. A beer can having a depressed top to form a drinking cup with a drinking lip and a relatively smooth and unobstructed bottom adjacent the lip and having a bead on the outside of the drinking lip permitting an opener to pry under the lip for indenting an adjacent portion of the bottom toward the wall of the can to form a hole adjacent the drinking lip, the entire bottom of the cup being free to drain into the hole when the can stands in upright position.

CHARLES E. BERTELS.
